VACUUM PUMP

Dan McDonald, Los Angeles, Calif., assignor to
 Master Filters, Inc., Los Angeles, Calif., a cor-
 poration of Nevada

Application January 3, 1933, Serial No. 649,326
 Renewed March 7, 1935

17 Claims. (Cl. 230—108)

This invention relates to pumps; and has for its object to provide simple but efficient fluid impelling means for creating suction and thereby particularly adapting the invention to vacuum pumps, and also adapted for pressure discharge of the fluid for embodiment of the invention in compressors.

More particularly it is the object of the invention to induce flow of a fluid by jet action of a motive fluid, with kinetic energy of the motive fluid produced by centrifugal force resulting from rotation of the motive fluid.

It is a further object of the invention to compound the jet action by a multi-stage jet or ejector with the jets centrifugally spaced and communicating for centrifugal flow of fluid through the series of jets which are subject to rotation, whereby centrifugal force imparts additional kinetic energy to the motive fluid at the succeeding jets, and the kinetic energy which is not expended at a preceding jet is utilized at a succeeding jet.

It is a still further object of the invention to entrain a fluid by jet action of a motive fluid, and then accelerate the combined flow by centrifugal force so that a large volume of the entrained fluid may be impelled at high velocity, thereby producing a high vacuum at the intake for the entrained fluid and thus particularly adapting the device for use as a vacuum pump, and also providing for efficient compounding of the jet action, since the accelerated flow from one jet supplies the motive force for the next succeeding jet.

It is still a further object of the invention to compress the centrifugal flow so that a large volume of fluid may be entrained at the successive jets, with the multi-stage jet adapted for efficient operation when compounded to a substantial plurality of stages such as will produce a large volume and high velocity of flow.

It is a still further object of the invention to direct the flow along the normal path of travel of a centrifugally moving rotating mass, so as to offer no obstruction to free flow of the fluid; and to preferably restrict the flow as it moves centrifugally, so that it may be discharged at a pressure sufficient to overcome external resistance and thus adapt the device for use as a compressor when so desired.

It is a still further object of the invention to mount the inducing jet on a rotor which is journaled in a suitable housing, with an intake for the fluid which is to be entrained by the rotating jet projecting from the housing and communi-

cating with any desired circulating system for creating a high vacuum therein, and the entrained flow discharging from the rotor into the housing so as to create any desired pressure in the housing. The pump may thus be advantageously employed for evaporating a liquid by means of a vacuum, with the vapors drawn through the rotor and compressed and condensed in the housing, thereby particularly adapting the pump for extracting and recovering volatile liquids such as the solvents used in a dry cleaning plant, or for evaporating, compressing and condensing the refrigerant used in a mechanical refrigerating plant.

It is a still further object of the invention to particularly adapt the pump for evaporating and subsequently condensing a volatile liquid, by providing a cooling means in the housing of the pump, whereby the vapors which are discharged from the rotor may be readily condensed.

It is a still further object of the invention to preferably utilize as the impelling fluid, the same fluid medium as is adapted to be withdrawn from a circulating system by operation of the pump, so that when the discharge from the rotor has been condensed, the condensate supplies the motive fluid for subsequent operation of the pump, and the excess of said condensate comprises the liquid which is recovered for subsequent re-use in the circulating system.

It is a still further object of the invention to rotate the rotor at a constant speed adapted for efficient operation of the impelling jet, and to regulate the vacuum which is produced by the pump, by controlling the supply of motive fluid to the inducing jet.

Further objects of the invention will be readily understood from the following description of the accompanying drawings, in which:

Fig. 1 is a vertical section through a pump constructed in accordance with the invention.

Fig. 2 is a transverse section on the line 2—2 of Fig. 1.

Fig. 3 is a detail section on the line 3—3 of Fig. 1.

Fig. 4 is a detail side elevation of a fragment of the inducing jet, partly in axial section.

The pump comprises a rotor supporting an inducing jet, with motive fluid directed through the jet by centrifugal force resulting from rotation of the rotor, and the motive fluid is adapted to entrain a fluid medium for drawing the latter through the rotor and thereby producing

a vacuum at the intake for said fluid medium, and discharging the fluid medium from the rotor at a pressure sufficient to overcome external resistance.

5 The illustrated embodiment of the invention is particularly adapted for use in connection with a circulating system whereby the pump is adapted to evaporate and withdraw a volatile liquid and then compress and condense the vapors for 10 recovery in liquid form; and for this purpose the pump has an intake for the fluid medium which is to be entrained, with said intake communicating with the circulating system, e. g. a solvent extracting or a refrigerating system, and 15 the entrained vapors are compressed and condensed and collected in a closed housing which surrounds the rotor.

The closed housing of the pump is shown at 1, and a rotor is suspended therein from a shaft 2 which is journaled in the housing for rotation by a motor 3 mounted on the housing. The rotor comprises a support for the inducing jet, and may consist of vertically spaced discs 4—5, meeting at their outer peripheries as shown at 6 and with 25 the center of the lower disc preferably having a depending annular collar forming an inlet 7. An intake pipe 8 projects upwardly into housing 1 in alignment and communicating with inlet 7; and a liquid seal is provided between the stationary intake pipe and the rotor, and may be of the form disclosed and claimed in my co-pending application Ser. No. 639,627, filed October 26, 1932.

As an instance of this construction a bowl 10 may be suspended from disc 5 for rotation with 30 the rotor, and a flange 11 may project laterally from the upper end of stationary pipe 8 in restricted vertically spaced relation below the disc 5 and just clearing the inlet collar 7. The base of the bowl forms an inlet for fluid; and when 35 the pump is in operation, with the bowl 10 turning with the rotor, fluid is forced upwardly by centrifugal force along the inclined wall of the bowl and fills the outer peripheral portion of the space between flange 11 and disc 5, so as to provide a 40 liquid seal surrounding the intake pipe 8.

The fluid which is forced upwardly by centrifugal force at the periphery of bowl 10, constitutes the motive fluid for the inducing jet which is mounted between discs 4—5; and the inducing 45 jet preferably comprises a plurality of units of similar construction and preferably equidistantly circumferentially spaced and each comprising one or more jet elements. Each unit is shown as having a nozzle 12 mounted between the discs 4—5 with its bore 13 communicating at its lower end with the outer peripheral portion of bowl 10, and its outlet 14 opening radially outwardly into the 50 space between discs 4—5. The motive fluid which is discharged through outlet 14 thus provides a jet action for entraining and radially impelling the fluid medium which occupies the enclosed space between the discs 4—5 and surrounding the nozzles 12, and since this space is open to intake pipe 8 via the inlet collar 7, the entrained and 55 radially impelled fluid medium reduces the pressure at the intake pipe, so that with the motive fluid impelled at high velocity, and thereby entraining a large volume of the surrounding fluid medium and radially impelling the same at high 60 velocity, the pressure at the intake 8 may be so lowered as to produce a high vacuum.

The centrifugal force resulting from rotation of the rotor discharges the motive fluid through jet 14 at the desired velocity for entraining the 65 surrounding fluid medium, and circumferential slip-

page of the rotating motive fluid may be decreased by impellers which are adapted to turn with the rotor. In the present embodiment, such impeller blades 15 are suspended from the disc 5 in the restricted vertical space between the rotor and the flange 11, the blades being circumferentially spaced as shown in Fig. 2; and when the rotor is turned, the fluid which has been elevated in bowl 10 by centrifugal force, is thus forced radially outwardly through the jet 14.

When the motive fluid discharged from jet 14 has entrained the fluid medium from the surrounding space, the combined centrifugal flow is accelerated since the kinetic energy of the motive fluid is maintained by the centrifugal force resulting from continued rotation of the flow, thereby insuring high velocity of flow and entrainment of a large volume of the fluid medium; and the jet action is preferably compounded so that the kinetic energy of the motive fluid is utilized to its maximum for entraining and impelling the surrounding fluid medium. As an instance of such compounding, a series of successive nozzles 16 are mounted between the discs 4—5 for cooperation with each of the jets 14; and the jet 14 discharges 25 into the flaring mouth of a combining tube 17 which tapers toward its outer end so as to form one of the nozzles 16, with each of the series of nozzles in turn discharging into the flaring mouth of the next succeeding combining tube. The fluid discharged at each succeeding nozzle thus provides the motive fluid whereby the fluid medium in the space between discs 4—5 is entrained at the flaring mouth of the next combining tube; and as a consequence the kinetic energy of the motive 30 fluid, maintained by the centrifugal force resulting from rotation of the fluid, is successively expended at the multi-stage inducing jet, for entraining a large volume of the fluid medium from the space between discs 4—5, and discharging 35 the entrained fluid at high velocity.

The entrained fluid is directed along the normal path of travel of a rotating mass so as not to obstruct centrifugal discharge of the fluid; and for this purpose each series of nozzles 16 is 45 curvilinear, and preferably defines an involute as shown in Fig. 2. As shown in Fig. 4 the series of nozzles may be formed by spirally twisting an elongated metal strip so that each convolution of the spiral tapers from the flaring mouth of a 50 combining tube 17, to its opposite end which forms the restricted discharge orifice of a nozzle 16.

After compounding the jet action by the multi-stage inducing jet, the entrained flow is discharged from the periphery of the rotor; and the flow is preferably cross-sectionally restricted as it approaches the periphery of the rotor, so that it may be compressed for discharge at a pressure adapted to overcome external resistance. 55 For this purpose the multi-stage jet terminates short of the outer periphery of the rotor, with the last nozzle 16 preferably opening into an annular ring 20 which is mounted between discs 4—5; and a compression tube 21 which is mounted between discs 4—5, communicates with the last nozzle 16 at the ring 20, and extends to and opens through the outer periphery 6 of the rotor, with the tube continuing the involute of the multi-stage jet and tapering slightly toward its outer 60 end which discharges externally of the rotor as shown at 22. The annular space between discs 4—5 from which the fluid medium is drawn into the multi-stage jet is thus closed at its outer periphery by ring 20, so that suction resulting 70

from entrainment of the fluid medium reduces the pressure in the enclosed annular space for creating a vacuum at intake pipe 8; and the entrained fluid is compressed and discharged 5 through the involute compression tube 21 so there is no resistance to flow of the fluid along the normal path of travel of a rotating mass, and the fluid is discharged under pressure from the compression tube into the surrounding housing 1.

The invention thus provides an ejector for entraining a fluid medium by a motive fluid, so as to reduce the pressure at the intake for the fluid medium and build up pressure at its discharge, 15 with the kinetic energy for the motive fluid produced by the centrifugal force resulting from rotation of a rotor on which the inducing jet is mounted, and the inducing jet comprising a multi-stage jet whereby the centrifugal force of 20 rotation maintains the kinetic energy of the motive fluid for use at the successive jets, in order that its maximum energy may be utilized for entraining and impelling the fluid medium, thereby entraining such volume of the fluid medium and compressing the same and discharging it at such velocity as to respectively produce 25 an appreciable vacuum and an appreciable pressure at the intake and discharge of the rotor. Any suitable liquid may be employed as the motive fluid; and the invention is particularly adapted to pumping a fluid medium such as a readily compressible gas, since such an entrained fluid may be readily compressed at the successive jets, and thus insure efficient operation 30 when the ejector is compounded to an appreciable plurality of stages adapted to entrain such volume of gas and impel the same at such velocity as to provide a pump of large capacity and adapted to produce a relatively high vacuum.

When the pump is employed for withdrawing vapors through intake 8, the entrained vapors which are compressed in tube 21 are to a large measure condensed in said tube before discharge 45 from the rotor into the closed housing 1; and pressure is built up in the closed housing for condensing any remaining vapors, and a cooling means may be provided in the closed housing for expediting condensation. The cooling means 50 may be a coil 25 mounted in the lower portion of housing 1 and adapted for circulation of a cooling liquid via an intake 26 and a discharge 27; and the cooling liquid may be circulated by a rotary pump 28 which may be mounted on motor 3 with an extension of the motor shaft forming the pump shaft. The intake 29 to the rotary pump is connected to a source of supply for a cooling medium such as water, and the outlet 30 of the pump is connected by pipe 31 to the intake 26 of the cooling coil. A pipe 32 is connected to the discharge 21 of the cooling coil, and may lead to a usual tower; and the cooling medium 55 is preferably adapted for circulation radially outwardly through successive annuli of its cooling coil, so that the coldest condensate is at the center of housing 1.

The condensate collecting in housing 1 may be withdrawn by overflowing into a stand-pipe 35 which projects into the housing; and the motive fluid for operating the pump may be a liquid form of the same fluid as that which the pump is adapted to withdraw through the intake pipe 8, so that the condensate collecting at the center of housing 1 below the level of the mouth of stand-pipe 35, and which is the condensate of lowest

temperature, is the source of supply for the motive fluid which is drawn upwardly through bowl 10 when the pump is in operation, with the excess of said condensate overflowing into the stand-pipe for ready recovery.

The rotor of the pump is preferably driven at constant speed, with the pump regulated by controlling the supply of motive fluid to the inducing jet; and for this purpose the intake at the lower end of bowl 10 is provided with a valvular control. As an instance of this arrangement a non-rotating sleeve 36 may project downwardly from the open lower end of the bowl, with an external flange 37 of the sleeve in restricted vertically spaced relation above an internal flange 38 of the bowl, so as to form a liquid seal between the rotating bowl and the non-rotating sleeve, of the same type as that which is formed between flange 11 of stationary pipe 8 and the cooperating disc 5 of the rotor. The sleeve 36 is preferably supported by a stationary annular baffle 39 which surrounds bowl 10, with the annular baffle suspended from a transverse partition plate 40 which is mounted in housing 1 below the rotor and above the level of the fluid which is contained in the housing. The plate 40 may be suspended from radial fins 41 which project into housing 1 from its peripheral wall, with the space above and below the transverse partition communicating at the circumferential spaces between the radial fins; and rotary agitation of the discharge from ports 22, which is collected and condensed in the lower portion of housing 1, is thus arrested by the fins 41, plate 40 and baffle 39. The motive fluid which is drawn into bowl 10 from the center of housing 1, may be filtered by an annular vertical filtering medium 42 extending from plate 40 to the base of housing 1 and surrounding the inlet to the bowl; and the pressure in bowl 10 and in housing 1 may be equalized through pipes 43 opening into the bowl below flange 11, and communicating with that portion of the housing 1 which is above plate 40.

The valvular control for the inlet to bowl 10 is mounted on sleeve 36; and may comprise a stationary disc 45 closing the inlet to the bowl and having an annular series of ports 46, with a cooperating disc 47 journaled on pipe 8 as shown at 48, and having an annular series of ports 49 adapted for variable alignment with ports 46 by rotatably adjusting the disc 47 with relation to the disc 45. The disc 47 may be rotatably adjusted by an operating connection projecting exteriorly of housing 1, and shown as comprising a lug 50 depending from disc 47 and adapted for engagement by a crank 51 of an operating rod 52 which is journaled in housing 1 as shown at 53, and which projects outside the housing where it is provided with an operating head 54.

The invention by providing a vacuum at intake pipe 8, and also providing for compressing and condensing the vapors which are drawn-off by the vacuum, is particularly applicable to either a solvent extracting plant or a mechanical refrigerating plant. For this purpose the intake pipe 8 may be connected to one side of the circulating system of such a plant by means of a coupling 56, with the stand-pipe 35 connected to the opposite side of the circulating system by a coupling 57. The housing 1 is filled to the level of the mouth of stand-pipe 35, with the solvent which is to be withdrawn and recovered from an extracting plant or with the refrigerant which is to be evaporated and then compressed and

condensed for usual cycle of operation in a mechanical refrigerating system; and the solvent to be extracted, for example the solvent used in a dry cleaning plant, or the refrigerant for a refrigerating plant, may be trichlorethylene, in which case it is a body of this liquid which is contained in housing 1. When the pump is in operation the coldest trichlorethylene from the center of the housing 1 is drawn upwardly through bowl 10 by centrifugal force, and is impelled by centrifugal force and the blades 15 through the multi-stage jet of the rotor so as to create an appreciable vacuum at intake pipe 8. The trichlorethylene in which articles have been cleaned in a dry cleaning plant or the trichlorethylene employed as the refrigerant in a refrigerating plant, may thus be evaporated and drawn into pipe 8; and the trichlorethylene vapors are to a large extent condensed in compression tube 21, due to their compression in said tube and to the lower temperature of the cold trichlorethylene which is the impelling liquid and with which the entrained vapors are in intimate contact, and condensation is then completed in housing 1, so that the condensed trichlorethylene may be withdrawn through stand-pipe 35 and used over again in the plant.

I claim:

1. In combination, means for rotating a motive fluid for impelling the same by centrifugal force, means for entraining a fluid medium by the impelled motive fluid, and means for regulating the supply of the motive fluid.
2. In combination, means for rotating a motive fluid for impelling the same by centrifugal force, means for entraining a fluid medium by the impelled motive fluid, and means rotating with the fluid rotating means for delivering the entrained flow along a curvilinear path of travel.
3. In combination, means for rotating a motive fluid for impelling the same by centrifugal force, means for entraining a fluid medium by the impelled motive fluid, and means for delivering the entrained flow in a stream of reduced cross-sectional area.
4. In combination, means for rotating a motive fluid for centrifugally impelling the same, and means for entraining a fluid medium by the impelled motive fluid at successive points along the centrifugal path of travel of the motive fluid.
5. In combination, a multi-stage jet for a motive fluid having its jet elements centrifugally one beyond another, means for rotating the jet for centrifugally impelling the motive fluid through the successive jet elements, and a combining tube cooperating with each element of the multi-stage jet for entraining a fluid medium.
6. In combination, means for rotating a motive fluid for impelling the same by centrifugal force, means for entraining and delivering a fluid medium by the impelled motive fluid, means for collecting the delivered flow, means for supplying the collected flow for use as the motive fluid, and means for equalizing the pressure in said collecting and supplying means.
7. In combination, a rotor adapted to rotate a motive fluid for impelling said fluid by centrifugal force, means for entraining and delivering a

fluid medium by the impelled motive fluid, a stationary intake for said fluid medium, and a liquid seal between the rotor and the intake.

8. In combination, means for rotating a motive fluid for impelling the same by centrifugal force, means for entraining a fluid medium by the impelled motive fluid, and means for confining and centrifugally delivering the entrained flow.

9. In combination, means for rotating a motive fluid for impelling the same by centrifugal force, means for entraining a fluid medium by the impelled motive fluid, and means for confining and delivering the entrained flow along a path of travel extending radially outwardly and rearwardly curving with relation to the direction of rotation.

10. In combination, means for rotating a motive fluid for impelling the same by centrifugal force, means for entraining a fluid medium by the impelled motive fluid, and means rotating with the fluid rotating means for confining and centrifugally delivering the entrained flow.

11. In combination, means for rotating a motive fluid for impelling the same by centrifugal force, means for entraining a fluid medium by the impelled motive fluid, and means for gradually restricting and delivering the entrained flow.

12. In combination, means for rotating a motive fluid for impelling the same by centrifugal force, means for entraining a fluid medium by the impelled motive fluid, and means gradually restricting and centrifugally delivering the entrained flow.

13. In combination, means for rotating a motive fluid for impelling the same by centrifugal force, means for entraining a fluid medium by the impelled motive fluid, and means rotating with the fluid rotating means for gradually restricting and centrifugally delivering the entrained flow.

14. In combination, means for rotating a motive fluid for impelling the same by centrifugal force, means for entraining a fluid medium by the impelled motive fluid at successive points along the path of travel of the motive fluid, and means for confining and centrifugally delivering the entrained flow.

15. In combination, means for rotating a motive fluid for impelling the same by centrifugal force, means for entraining a fluid medium by the impelled motive fluid at successive points along the path of travel of the motive fluid, and means for gradually restricting and delivering the entrained flow.

16. In combination, means for rotating a motive fluid for impelling the same by centrifugal force, means for entraining a fluid medium by the impelled motive fluid at successive points along the path of travel of the motive fluid, and means for gradually restricting and centrifugally delivering the entrained flow.

17. In combination, means for rotating a motive fluid for centrifugally impelling the same along a curvilinear path of travel, and means for entraining a fluid medium by the impelled motive fluid at successive points along the path of travel of the motive fluid.

DAN McDONALD.
